CLAIM

The ornamental design for a printer stand, as shown.

DESCRIPTION

FIG. 1 is a top, front, and right perspective view of a printer stand showing my new design;

FIG. 2 is a rear, bottom, and left perspective view thereof;

FIG. 3 is a front elevational view thereof;

FIG. 4 is a right side elevational view thereof, the left side elevational view being a mirror image thereof.

FIG. 1

FIG. 2

FIG. 3

FIG. 4
